United States Patent Office.

DANIEL A. HALL AND DAVID GARRISON, OF PHILADELPHIA, PENNSYLVANIA, ASSIGNORS TO SWAN & CLARK, OF SAME PLACE.

Design No. 4,602, dated January 24, 1871.

DESIGN FOR BOXES FOR TOPS OF BUREAUS.

The Schedule referred to in these Letters Patent and making part of the same.

To all whom it may concern:

Be it known that we, DANIEL A. HALL and DAVID GARRISON, of the city of Philadelphia, and State of Pennsylvania, have invented or produced a new and original Design for the Boxes for the Tops of Bureaus; and we do hereby declare the following to a full, clear, and exact description of the same, reference being had to the accompanying drawing making a part of this specification, in which—

Figure 1 represents, in perspective, one of said boxes;

Figure 2 represents a top plan of the same; and

Figure 3 represents a vertical section through the box.

The design in question consists—

First, in the shape of the box; and

Secondly, in the ornamentation thereof, its purpose and object being to be used as top-boxes for bureaus.

The lid A of the box projects slightly over the body thereof, and its edge is composed of a series of reversed curves, *a b c d*, with a beveled moulding, *e*, wrought thereon.

That portion of the body B of the box which is covered by the lid A, is also of a series of corresponding reversed curves, while the portion back of the lid may be rectangular.

The lower edge of the box is ornamented with a ribband molding, *f*, composed of a series of pointed or leaf-shaped figures, *g*, around and over the under edges of which a second series of pointed figures, *i*, is placed.

The projection of the molding *f* is seen in the section, fig. 3.

What we claim is—

1. The form or shape of the box and lid, as herein described and represented.

2. The ornamentation of the box, as herein described and represented.

DANIEL A. HALL.
DAVID GARRISON.
